UNITED STATES PATENT OFFICE.

EDWARD S. JONES, OF MOBILE, ALABAMA, ASSIGNOR OF ONE-HALF TO MARTIN VAN HEUVEL, OF MOBILE, ALABAMA.

SHIP-DAVIT.

1,218,087.

Specification of Letters Patent.

Patented Mar. 6, 1917.

Application filed May 11, 1916. Serial No. 96,925.

To all whom it may concern:

Be it known that I, EDWARD S. JONES, a citizen of the United States, and resident of Mobile, in the county of Mobile and 5 State of Alabama, have invented certain new and useful Improvements in Ship-Davits, of which the following is a specification.

My invention relates to ship davits and 10 more particularly to a movable davit for supporting life-boats.

An object of the present invention is to provide a ship davit for supporting life-boats in such a manner as to allow them to 15 be easily lowered to the water and yet preventing them from contacting with the sides of the ship.

Another important object of the present invention is to provide a ship davit having 20 means associated therewith whereby the persons using the life-boat may lower the boat without any assistance from any person on the deck of the ship.

A further object of the invention is to 25 provide an apparatus of the abovementioned character for supporting life-boats embodying means whereby the life-boat may be easily and quickly disengaged from the apparatus when the life-boat reaches the water.

30 A still further object of the invention is to provide a ship davit that is mounted in such a manner as to prevent it from being broken or bent should the ship strike against its landing place or other objects.

35 With the above and other objects in view, my invention consists in the constructions, arrangements of parts and operations that will be hereinafter described and illustrated in the accompanying drawings, in which—

40 Figure 1 is an elevation showing a portion of the side of a ship with the life-boat supporting davit mounted thereon.

Fig. 2 is a transverse sectional view 45 through one side of the ship and showing a side view of the life-boat supporting davit in position when not in use. This figure also shows the life-boat supporting davit being lowered.

Fig. 3 is an enlarged view of the upper 50 end of one of the davits showing the manually operable means for lowering the same.

Fig. 4 shows a modified way of attaching the davits to the life-boat.

Referring more particularly to the draw-

ing, the numeral 5 denotes a ship which may 55 be of any type.

Formed in the side of the ship and extending vertically thereof are relatively wide longitudinal channels 6 which extend to the top deck of the ship.

60 Mounted in these longitudinal channels adjacent their lower extremities are the angular bearing plates 7. Pivotedly connected with these bearing plates 7 as at 9 are the supporting davits 8 which normally 65 lie within the longitudinal channel 6 and extend above the top deck of the ship. These davits are outwardly and downwardly curved at their upper ends and terminate in rectangular enlargements 10. Mounted 70 in the ends of the enlargements 10 are the yokes 11 which are loosely engaged with life-boat supporting hooks 12.

75 The numeral 13 indicates a life-boat of any conventional type having mounted in its opposite ends U-shaped members 14 which are engaged with the hooks 12 to support the life-boat at the top deck of the ship.

80 Mounted in each of the enlargements 10 is a shaft 15 carrying a gear 16 upon one end and a windlass 17 upon its opposite end. Also mounted upon each of these enlargements is a crank handle 18 carrying a gear 19 which meshes with the gear 16 to rotate the windlasses. In order to allow the windlasses to be held against rotation in either direction, a reversible pawl 20 is pivoted 85 upon each of the enlargements 10 adjacent the gear 19 to engage the same. Secured to the windlasses 17 are cables or ropes 21 90 which are adapted to be wound therearound. One end of these cables is extended around pulleys 22 that are mounted upon the upper deck of the ship, and secured to securing members 23 which are mounted on the 95 davits 8.

Engaged about each of the windlasses 17 is a brake band 24. Mounted upon each of the davits 8 adjacent to the gears 19 is a crank handle 27 carrying a link 28. These 100 links are pivotally connected at both ends with the ends of the brake bands 24.

105 Mounted within the longitudinal channel 6 are the vertical rods 29 having grooved rollers 30 mounted in their upper ends. These rods 29 extend above the ship and in alinement with the davits 8.

A windlass 31 for each davit 8 is mount-

ed upon the ship. Only one of which is shown in the drawings, it being obvious that one windlass 31 is necessary for each davit. Cables or ropes 32 are extended over the rollers 30 and connected with the davits 8, 5 as at 33, and the windlasses 31. Carried by the rods 29 are hooks 34 which engage eyes carried by the davits 8 to support the same in a vertical position.

Having described the various parts of my 10 invention, the manner of operation will now be set forth: The life-boat being in the position shown in Fig. 1, the hooks 34 are disengaged from the davits 8. A person now 15 rotates each of the windlasses 17 to slowly unwind the ropes or cables 21, which by reason of gravity will allow the davits to swing downwardly to the water. Should it be desired to stop the life-boat on its downward 20 movement or to lower it more slowly, the crank handles 27 are rotated to tighten the brake bands. After the life-boat has reached the water, the hooks 12 are disengaged from the yokes 14. The windlasses 31 are now 25 rotated to bring the davits to their normal position. It will be seen that these windlasses 31 may be also used to help lower the life-boat should the load therein be too heavy to be handled from the windlasses 17 alone, or 30 they may alone be used to lower the life-boat.

In Fig. 4, a different manner of engaging the hooks 12 with the life-boat is shown. A cable or other flexible element 35 adapted to 35 be engaged by one of the hooks is permanently attached at one end to the life-boat and having a head 36 upon its free end which normally lies upon the upper edge of the life-boat. Pivotaly mounted upon the 40 upper edge of the life-boat as at 37 is a lever

38 having an arcuate seat 39 therein which engages the cable adjacent the head 36. A yoke 40 is swiveled in the upper edge of the life-boat and normally engages the free end of the lever 37 to securely retain the same in 45 engagement with the cable 35. When it is desired to release the hooks 12 from the cables 35, the yoke 40 is disengaged from the lever 37 which in turn is disengaged from the cable 35.

From the foregoing description taken in connection with the accompanying drawing the advantages of the construction and method of operation will be readily understood by those skilled in the art to which the 55 invention appertains, and while I have described the principle of operation, together with the apparatus which I now consider to be the best embodiment thereof, I desire to have it understood that the apparatus shown is merely illustrative and that such changes may be made when desired as fall within the scope of the appended claims.

What is claimed is:

1. The combination with a ship, of life-boat supporting davits pivotally mounted thereon, a windlass mounted upon each of the davits, pulleys mounted on the ship, and flexible elements connected with the davits and windlasses and engaging the pulleys.
2. The combination with a ship, of life-boat supporting davits pivotally mounted thereon, an enlargement carried upon the free end of each of the davits, a windlass mounted upon each of the enlargements, pulleys mounted on the ship, and flexible elements connected with the davits and windlasses and engaging the pulleys.

EDWARD S. JONES.
